CHARLES EMIL GERBAUD, OF PARIS, FRANCE.

SPARK-PLUG MOLD.

Application filed December 12, 1919. Serial No. 344,493.

To all whom it may concern:

Be it known that I, CHARLES EMIL GERBAUD, of 102 Rue Pelleport, Paris, France, manufacturer of glassware, have invented 5
5 Improvements in Spark-Plug Molds, of which the following is a full, clear, and exact description.

This invention relates to molds for use in the manufacture of glass-insulated sparking 10 plugs, by casting the glass insulation in the metal shell of the plug.

Sparkings plugs have already been designed in which the insulating body consists of a mass of glass cast in the shell of the 15 plug, but the existing processes have never been able to give good results, for the reason that when the molten mass is introduced and compressed direct in the shell, the molecules of glass are firmly pressed against each other, 20 and experience has shown that the result of this compression is to cause the formation, in the mass of glass, on cooling, of cracks through which leakages can occur.

The object of the present invention is to 25 provide a mold arranged in such a way as to enable the glass insulation to be cast on to the axial electrode inside the shell under such conditions that the inconvenience described cannot arise.

According to this invention a mold is provided with a pouring gate which is offset, 30 axially, in relation to that portion of the mold in which the glass insulation is to be cast, and communicates with the body of the 35 mold by way of an opening of smaller diameter.

By virtue of this device the molten glass filling the shell is relieved to a large extent of the pressure of the column of glass in the 40 pouring gate, and, in addition, of the pressure exerted on said column of glass during the pouring process.

Experience has shewn that this arrangement of the mold enables the glass insulation 45 to be cast in the metal shell of the plug without any risk of the formation, within the mass of glass whilst cooling, of cracks through which leakages could occur, as in the case when the introduced glass is compressed direct in the shell.

In some cases a plug carrier may be provided inside the mold, to facilitate the removal of the plug from the mold, and enable such removal to be effected directly af-

ter the glass has been cast, so that the mold 55 need not be idle during the time the glass is cooling, but can be used at once for making another plug.

This plug carrier comprises a lower ring, 60 resting on the bottom of the mold and supporting the shell of the plug, and a cap covering said shell, said ring and cap being provided with handles which enable them to be easily held when the plug is being taken out of the mold, so that the plug can be taken 65 out of the mold as soon as the glass has been cast.

The invention is illustrated by the accompanying drawings in which:

Figs. 1 to 5 show one form of the invention;

Fig. 1 being a front elevation of the inside of one of the shells of the mold,

Fig. 2 being a plan of the mold,

Fig. 3 a vertical section of the mold along 75 the line A—A of Fig. 2, the shell of the plug and the plug carrier being shewn in position inside the mold;

Fig. 4 being a horizontal section, along the line B—B of Fig. 3, and Fig. 5 being a sectional elevation of detail shewing the core intended to keep the electrode rod in position inside the mold.

Fig. 6 is a vertical section of a mold for the manufacture of a plug with a spark-gap 85 electrode.

Figs. 7 to 10 shew the improved type of mold with an internal plug carrier, Fig. 7 being a vertical section along the line C—C of Figure 8; Figs. 8 and 9 shewing the mold 90 in plan, open and closed respectively; whilst Fig. 10 shews the plug and the device by which it is lifted out of the mold.

The type of mold represented in Figs. 1 to 5, which is similar to the molds used for 95 glassware, is composed of two shells *a*, hinged together and provided with an internal cavity *a*¹, which, when the mold is closed, houses the metal shell *b* of the plug, which has been made beforehand in the ordinary way.

The lower portion of each of the mold shells is provided with a second cavity *a*² for the reception of a central core *c* (Figs. 3 to 5) the upper surface of which is formed 105 with a hole *c*¹ adapted to receive the lower end of a rod *d* which is to form the axial electrode of the plug. The upper end of

this rod is received in a recess a^3 provided in each of the mold shells a .

The upper portion of the mold shells is provided with a pouring gate e , which is offset, axially, in relation to the internal cavity of the mold as formed by the recesses a^1 and housing the plug shell b , said gate communicating with said internal cavity by means of an opening e^1 of small diameter.

10 Before the glass is poured, the plug shell b and the electrode rod d are heated by any means whatsoever.

The said plug shell b and electrode rod d having been placed in position, as shewn in Fig. 3, inside the mold, and the latter closed, molten glass f or preferably a good sodium silicate, is poured into the gate e ; and pressure is then exerted on the surface of said glass, either by means of a tamping tool g , a piston or any other device. Under this pressure the molten glass passes through the small opening e^1 and fills the plug shell b in such a way that a part of the upper portion of the internal cavities a^1 of the mold 25 remains empty above the plug shell.

In consequence of the axially offset arrangement of the pouring gate e and the small section of the opening e^1 only a small part of the pressure exerted on the glass is transmitted to the glass introduced into the plug shell b , and under these conditions this glass is not subjected to any harmful pressure.

The glass thus poured into the shell b adheres, in cooling, to the inner surface of the latter and to the electrode rod d , and under these conditions, binds these two together completely and makes the plug perfectly tight, whatever may be the degree of compression of the gases inside the engine on which the said plug is mounted. Moreover, this glass by reason of its perfect homogeneity, is capable of withstanding all expansion stresses.

45 It should also be stated that this arrangement of the mold ensures the electrode being perfectly centered in relation to the plug shell.

Fig. 6 shows the application of the improved mold to the manufacture of a sparking plug, the electrode rod of which is provided with a spark gap. In this case the axial electrode is composed of two lengths of rod d^1 and d^2 , which, when the electrode is assembled inside the mold, are connected together by an insulating sleeve h , of glass for example, which holds these two lengths of rod in accurate position opposite each other at the desired distance apart.

60 Figs. 7 to 10 illustrate another form of the improved mold, provided with an internal plug carrier.

In this modification the two shells a of the mold are pivoted about a shaft i , mounted on a plate j supported by two pillars k

upstanding from a base plate l . A projection j^1 on the plate j supports a movable ring m provided with a handle m^1 . In this ring fits the lower cylindrical portion of the metal shell b of the plug in which the glass insulation is to be cast.

The plate j is provided with a threaded central bore, traversed by a rod n adapted to support the axial electrode d of the plug. This rod n , the lower end of which is provided with a handle or hand wheel o , is threaded at n^1 to screw into the threaded bore of the plate j ; and at its upper end has an axial recess in which the electrode rod d of the plug rests freely.

At the upper part of the shell b a cap p is applied, said cap being furnished with a handle p^1 and formed with a filling aperture p^2 adapted to communicate with the pouring gate e offset axially, as above mentioned, relatively to the shell b in which the glass insulation is to be cast. The cap p is also formed with a central aperture adapted to receive the axial electrode d .

The rod n is also provided with a shoulder which, when the rod is moved upward by screwing it into the plate j of the mold, comes in contact with the edge of the lower cylindrical portion of the plug shell b , thus lifting the plug and its cap p and causing the latter to bear against the upper portion of the cavity provided in each of the shells of the mold. Moreover, by this means, the electrode rod d carried by the rod n , is adjusted at the proper height inside the plug shell b .

A piston g^1 , adapted to force the molten glass into the plug shell, is slidable in the pouring gate e .

The plug shell b into which the insulating glass is to be poured is thus held in position inside the mold by the lower ring m and the cap p .

As already stated, the plug shell b and the electrode rod d are heated by any means whatsoever, before the glass is poured.

When the pouring is effected pressure is exerted by the piston g^1 on the mass of glass contained in the gate e and when the pouring has been completed, the mold is opened and the rod n is unscrewed so as to release it from the axial electrode d and the ring m . Then, by taking hold of the handles m^1 , p^1 , the plug supported between the ring m and the cap p —as shewn in Fig. 10—is lifted out of the mold.

The plug shell b being closed at the upper end by the cap p , the mass of glass enclosed in it cannot suffer any deformation during the removal from the mold, so that this operation can be performed while the glass is still in a plastic state. It is therefore no longer necessary to wait until the plug has cooled down completely before proceeding to detach it from the mold, and

consequently the mold can be used for making another plug immediately after the glass insulation has been poured.

Claims:

- 5 1. A mold for the manufacture of spark plugs for internal combustion engines having two chill mold sections articulated between each other analogous to the chill mold sections used in the manufacture of 55 glass, said mold sections each being provided with cooperating cavities, one in each mold section, and placed in such a manner to form an inside pocket within the mold sections for receiving the lower part of a 60 10 spark plug shell in which the glass insulator is to be cast, two other cooperating cavities, one in each mold section located out of the axis of the first-mentioned cavities, two narrow grooves respectively 65 15 on each of the chill mold sections cooperating to provide a restricted communication between the first and second mentioned cavities, two other cavities one in each mold section cooperating to receive an electrode bearer, said cavities opening through 70 20 the bottom of the mold sections, an electrode bearer located in and forming a seal to close the lower end of the last mentioned cavities, said electrode bearer having a reduced 75 25 upper end of a shape to project into and neatly fit the lower hollow end of the spark plug shell and provided with a central aperture for receiving the lower end of the usual central electrode, the two chill mold 80 30 sections being provided with cooperating seats opening into the upper end of the first mentioned cavity to receive the other end of the electrode.
2. A mold for the manufacture of glass- 85 35 insulated sparkings plugs for internal combustion engines, comprising: two hinged mold shells, similar to those of the molds used for glassware and having internal cavities adapted to house the shell of the plug 90 40 into which the glass-insulation is to be poured; a plate on which are mounted these two shells; an internal electrode-carrying core on which is mounted the axial electrode; a 95 45 pouring gate constituted by cavities provided in the two shells of the mold and hav-
- ing a common axis, when the mold is closed, axially offset in relation to the portion of the mold in which the glass-insulation is to be cast; an opening of small diameter putting the pouring gate in communication with the interior of the mold; a lower ring resting on the mold plate and serving to support the plug shell, the said ring being provided with a handle; a cap covering the said plug shell arranged on this ring, the said cap being provided with a handle; an opening in this cap for pouring the glass contained in the axially offset pouring gate. 55
3. A mold for the manufacture of glass-insulated sparking plugs for internal combustion engines, comprising: two hinged mold shells, similar to those of the molds used for glassware, and having internal cavities adapted to house the shell of the plug into which the glass-insulation is to be 60 60 poured; a plate on which are mounted these two shells; an electrode-carrying core screwed in the plate of the mold; a shoulder on this core, so arranged as to raise, during its upward movement produced by its screwing in the mold plate, the plug shell and the cap, so as to cause the latter to bear against the upper part of the cavity provided in each of the mold shells; a pouring gate constituted by cavities provided in the 65 65 two shells of the mold and having a common axis, when the mold is closed, axially offset in relation to the portion of the mold in which the glass-insulation is to be cast; an opening of small diameter putting the 70 70 pouring gate in communication with the interior of the mold; a lower ring resting on the mold plate and serving to support the plug shell, the said ring being provided with a handle; a cap covering the said plug shell arranged on this ring, the said cap being provided with a handle; an opening in this cap for pouring the glass contained in the axially offset pouring gate. 75
- The foregoing specification of my "Improvements in molds for the manufacture of glass-insulated sparking plugs for internal combustion engines" signed by me this 21st day of November 1919.
